PRINTING MECHANISM

Albert W. Mills, Endicott, N. Y., assignor to International Business Machines Corporation, New York, N. Y., a corporation of New York

Application August 11, 1934, Serial No. 739,409

5 Claims. (Cl. 101—93)

This invention relates to accounting machines and more particularly to improvements in the printing mechanism thereof. Tabulating machines have heretofore been constructed in general with impositive driving mechanism for positioning the type bars of the printing mechanism and where the number of type elements carried by a type bar has not been more than are required for printing the digits, such impositive arrangement has been very satisfactory. In printing mechanisms where type bars are provided with sufficient type elements to print all the characters of the alphabet in addition to the numerical characters, the weight of the entire bar has necessarily been increased and the inertia of the parts has tended to cause the type bar to lag behind the impositive driving mechanism. Other factors have also contributed towards interfering with the free movement of the type bars, such as stickiness, dust, oil, etc. With the present arrangement, positive means is provided for definitely and positively advancing the type bar to printing position so that upon the operation of the selecting mechanism timed to 25 select a particular character for printing, the type element will definitely be at the printing position.

A further feature of the invention is the provision of a pair of contacts associated with each 30 type bar selecting device which upon closure are adapted to complete a circuit through the adding magnet of an accumulator. This arrangement provides for a more definite relationship between the selection of a character for printing and the entry of a corresponding value into an accumulator.

In accordance with a modified form of the invention the type bar has associated therewith a light, intermediate bar which is not so readily 40 susceptible to retardation as the heavier type bar. This intermediate bar is differentially positioned in accordance with the value printed and the type bar moves upward therewith and is in turn positioned thereby. Should the type bar 45 lag during its advancing movement, it will nevertheless eventually come to rest with the proper character in printing position.

Various other objects and advantages of the 50 invention will be obvious from the following particular description of one form of mechanism embodying the invention or from an inspection of the accompanying drawings; and the invention also constitutes certain new and novel features of construction and combination of parts 55 hereinafter set forth and claimed.

In the drawings:
 Fig. 1 is a detail section of a type bar and the operating mechanism therefor.
 Fig. 2 is a detail of the operating cams for reciprocating the type bars.

The improved mechanism is shown in connection with a tabulator of the type shown in Patent No. 1,914,285, issued June 13, 1933 to J. R. Peirce, in which well known perforated records of the Hollerith type are successively fed past analyzing brushes 10 (Fig. 1) which, upon encountering a perforation in any one of the usual index point positions, will complete a circuit to printing magnet 11 which will attract its armature 12, drawing a call wire 13 to the right to cause latch 14 to release stopping pawl 15 so that the latter may rock in a clockwise direction under the influence of a spring 16.

The type bar structure comprises a type head 17 having type elements 18 thereon. The head 17 is carried by type bar 19 which is suitably mounted for vertical reciprocation. The lower end of the type bar is connected by a link 20 to an arm 21 which is pivoted at 22. Arm 21 has pivoted thereto at 23 a hook-shaped member 24 which is biased in a clockwise direction by a spring 25. Member 24 is adapted to engage the ledge of a crosshead 26 carried by arms 27 which are also pivoted at 22. Crosshead 26 is adapted to be oscillated by a pair of complementary cams 28 (Fig. 2) which are carried by the drive shaft 29 of the machine and which rock a bell crank follower 30 carried on a rod 31. Rod 31 also carries an arm 32 connected by a link 33 to an arm 34 on rod 35. Arms 36 supported on rod 35 have link connection 37 to the crosshead arms 27. As the crosshead 26 rocks in a clockwise direction synchronously with the movement of the record card past the analyzing brushes, the type bar 19 is elevated by virtue of the connection between the member 24 and the crosshead. Member 24 has pivoted thereto at 38 an intermediate bar 39 provided with teeth 40 which, as the bar 39 moves upwardly with the member, successively pass the toe of pawl 15 as the correspondingly numbered index point positions of the record card pass the analyzing brushes 10. Energization of the magnet 11 in response to a perforation in any position will trip pawl 15 and cause it to engage the correspondingly numbered tooth 40, thereby preventing further upward movement thereof. When such action takes place the continued upward movement of the crosshead 26 will cause the member 24 to cam away from the driving ledge of the crosshead and

the further upward movement of the connected arm 21 and crosshead 19 will therefore be interrupted.

Arm 21 has pivoted thereto a latching dog 41 which, when the arm 21 is thus released will engage one of the stepped notches 42 in a bar 43 to prevent retrograde movement of the associated parts.

The above describes the manner in which the type elements 18 are positioned for printing numerical characters. When alphabetic characters are to be printed, so-called zoning mechanism is brought into action which, by causing relative displacement between the type head 17 and type bar 19, will present the alphabetical characters to printing position. The particular zoning mechanism forms no part of the present invention and reference may be had to my copending application Serial No. 634,690, filed September 20, 1932 wherein such zoning mechanism is shown and described.

After all the type bars have been positioned, the usual printing hammer 44 is operated to strike an impression therefrom. Thereafter the crosshead 26 is moved downwardly to cause restoration of the type bars. As it begins its downward movement, a cam 45 carried by shaft 29 will engage an arm 46 carried by rod 47 and hold the latter in its rocked position while the type bars are being restored. Rod 47 carries a bail 48 which normally abuts the free ends of bars 43 to hold them in the position shown. The bars 43 are pivoted at 49 and urged against a stopping plate 50 by springs 51. During the restoring operation bars 43 are free to rock in a clockwise direction and will do so under the influence of the dogs 41 which, in order that the arms 21 may move downwardly, will push bar 43 to the left and the dogs 41 will rock clockwise 40 to their dotted line position, as shown in Fig. 1, with their free ends pointing upwardly toward the left.

The travel of crosshead 26 during the restoring operation is of sufficient extent so that dogs 45 41 pass beyond the lowermost step of bar 43 and as the crosshead begins its next ascent, bail 48 will again be in position behind the bars 43 and the pawls 41 will be cammed by the lowermost step of bar 43 back to the position where the 50 engaging end of the dog faces downwardly toward the left.

Member 24 has connected to its depending arm 24a, a link 60 whose opposite end is attached to the free end of a pivoted arm 61. A projection on arm 61 abuts against a blade of a pair of contacts 62 which upon closure complete a circuit to an adding magnet 63. The action is such that upon interruption of the upward movement of bar 39, the member 24 will be cammed in a counterclockwise direction and through link 60 will effect momentary closure of contacts 62 thus completing the adding circuit at a differential time depending upon the differential time at which the character is selected for printing.

While there has been shown and described and pointed out the fundamental novel features of the invention as applied to a single modification, it will be understood that various omis-

sions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In a printing mechanism, a type carrier movable to a plurality of printing positions, a driving element for the same having an invariable movement, latching means for positively coupling the carrier to the driving element for movement thereby in one direction, a bar pivoted to said latching means, means for operating said bar at differential times to effect unlatching of said carrier from said driving element, and constantly effective means for preventing retrograde movement of said carrier upon its release from the driving element.

2. In a printing mechanism, a type carrier movable to a plurality of printing positions, a driving element for the same having an invariable movement, latching means for coupling the carrier to the driving element for varying times during the advance movement of the element, electromagnetic means controlled by differentially timed electrical impulses for controlling the latching means to effect different durations of coupling between the carrier and the driving element, a spring urged latching bar for holding said carrier when released from the driving element, means for holding said bar in position and means for removing said holding means from said latching bar prior to the restoration of the carrier whereby the carrier will be released for restoration.

3. In a printing mechanism, a type carrier, means for advancing said carrier, means for interrupting the same at differential times to present different characters in position for printing, means for holding said carrier in position comprising a pivoted locking bar and a latching dog connected to the carrier and means for causing said bar to rock out of operative engagement with said dog to permit restoration of the carrier.

4. In a printing mechanism, a reciprocable type carrier, a pivoted operating arm, connected thereto, means for positively rocking said arm to reciprocate said carrier, means for disconnecting said arm from said rocking means to interrupt the movement of the carrier and means carried by the arm for holding the same in position upon its release from the rocking means.

5. In a printing mechanism, a reciprocable type carrier, a pivoted operating arm connected thereto, an invariably movable driving element, a latch carried by said arm for connecting the same to said element for positive movement therewith whereby said carrier will be advanced, means for disconnecting said latch from said element at differential times during its movement and means including a spring-pressed dog and locking bar for holding the arm in position after its release from said driving element.

ALBERT W. MILLS.
